UNITED STATES PATENT OFFICE.

ALBIN MILLER, OF PRINCE GEORGE, BRITISH COLUMBIA, CANADA.

BOTTLE.

1,419,747.

Specification of Letters Patent. Patented June 13, 1922.

Application filed February 10, 1921. Serial No. 444,056.

To all whom it may concern:

Be it known that ALBIN MILLER, subject of the King of England, residing at Prince George, in the Province of British Columbia 5 and Dominion of Canada, has invented new and useful Improvements in Bottles, of which the following is a specification.

The object of the invention is to provide a construction of bottle and closure for the 10 same, particularly involving means whereby the closure is seated and secured in place, with the purpose of securing an effective seal for the bottle when filled and closed and of giving ready access to the contents 15 thereof when desired while preventing the re-sealing or closing of the bottle by means of an ordinary cork, and hence of providing a bottle which can not be commercially re-filled, to the end that it may serve as a 20 safe and efficient container for original package goods or products; and with this object in view the invention consists in a construction and combination of parts of which a preferred embodiment is shown in the drawing 25 wherein:

Figure 1 is a sectional view of the neck portion of a bottle constructed in accordance with the invention, the closing and sealing means being arranged in the operative position.

Figure 2 is a similar view showing an intermediate step in the method of sealing the bottle.

Figures 3 and 4 are transverse sections on 35 the planes indicated respectively by the lines 3—3 and 4—4 of Figure 1.

Figure 5 is a detail view of the packing disk.

The receptacle in connection with which 40 the sealing device embodying the invention is shown applied is of the bottle type having a neck 10 in which adjacent to the upper edge is arranged a seat 11 disposed in a plane transverse to the axis of the neck and 45 formed by a rib 12 which projects inwardly from the wall of the neck and preferably terminates in a sharp inwardly directed edge, as shown clearly in Figures 1 and 2, an annual groove 13 being formed in the wall 50 of the neck and above the ledge or rib constituting the seat, the lower wall of the groove or channel being in the plane of the seat formed by the upper surface of said ledge or rib to properly support in a flat 55 condition a packing disk 14, shown in detail in Figure 5, which may be constructed of

cardboard or like flexible yielding material. The diameter of the packing disk is preferably such as to extend into the groove or channel 13, and it is secured in place to 60 seal the neck of the bottle by means of a retaining disk 15 of metal originally constructed in the form of a spherical segment, as shown in Figure 2, to provide upper convex and under concave surfaces with the rim 65 or periphery thereof upturned or grooved reversely as shown at 16, said retaining disk being also of a diameter which in its original form is adapted to fit into the annular groove or channel in the inner surface of the 70 neck. After positioning the retaining disk in contact with and resting upon the packing disk as shown in Figure 2, the center or upwardly bulged portion of the retaining disk is forced downward into contact with 75 the upper surface of the packing disk to the position indicated in Figure 1, thus circumferentially expanding the retaining disk to cause the turned periphery thereof to curl or bead backward or inwardly over the 80 outer surface of the disk to snugly fit and occupy the groove or channel of which the wall is preferably curved transversely for the purpose of directing the bending of the 85 said periphery of the retaining disk. Therefore when properly seated and locked in place by the depression of its center as above indicated, the retaining disk as shown in Figure 1 is disposed bodily in parallelism and contact with the packing disk and has 90 its periphery recurved or rebent inwardly to form a bead 17 which effects the compression of the packing disk to afford a liquid tight joint between the sealing means and the neck of the bottle, and while the retaining 95 and packing disks may be punctured within the area circumscribed by the sharp edges of the inwardly directed ribs or ledges 12, to permit of the removal of the contents 100 of the bottle by pouring, said puncture being effected by any suitable sharp instrument, the disengagement of the beaded edge of the retaining disk from the groove or channel in the wall of the bottle neck is practically impossible or is so difficult as to serve as a 105 means of preventing the unauthorized reuse of the bottle. Moreover even if the rim portion of the retaining disk should be removed from the bottle neck, the location of the ledge or rib 12 adjacent to the upper or 110 lip portion of the bottle neck will prevent the effective application of a cork or other usual

means of sealing a bottle. Exterioly the bottle neck is of cylindrical form or is unbeaded so as to afford no seat for a closure of the cap type.

5 As a further means of preventing the unauthorized use of a cork, the bottle neck is preferably provided below the plane of the rib or ledge 12 with inwardly projecting knobs or bosses 18 preferably extending 10 inward beyond the inner edge of the seat formed by said rib or ledge.

Having described the invention, what is claimed as new and useful is:—

15 1. A bottle or like receptacle having its neck provided adjacent to its lip edge with a transverse inwardly projecting seat or ledge and a superjacent annular groove or channel in combination with a metallic sealing disk of concavo-convex construction provided with a reverse peripheral edge for engagement with said groove or channel, the central portion of said disk being compressible 20 to circumferentially expand the disk.

25 2. A bottle or like receptacle having its neck provided adjacent to its lip edge with a transverse inwardly projecting seat or ledge and a superjacent annular groove or channel in combination with a metallic sealing disk of concavo-convex construction provided with a reverse peripheral edge for engagement with said groove or channel, the central portion of said disk being compressible 30 to circumferentially expand the disk, the wall of said groove or channel being concaved 35 transversely to direct the inward curvature of the peripheral edge of said disk.

3. A bottle or like receptacle having its neck provided adjacent to its lip edge with a transverse inwardly projecting seat or ledge and a superjacent annular groove or channel 40 in combination with a packing disk fitted upon said seat and a pliable, centrally compressible spherically segmental retaining disk seated upon said packing disk and having a returned or inwardly bent peripheral 45 edge extending into said groove or channel and inwardly returnable by contact with the wall of said groove or channel by the circumferential expansion of the disk due to the depression of the central portion thereof. 50

4. A bottle or like receptacle having its neck portion provided adjacent to its lip edge with a transverse seat for a sealing device, the seat being formed by an inwardly directed rib or ledge having a sharp inner 55 edge, and said neck further being provided below the plane of said seat with inwardly directed knobs or bosses.

5. A bottle or like receptacle having its neck portion provided adjacent to its lip 60 edge with a transverse seat for a sealing device, the seat being formed by an inwardly directed rib or ledge having a sharp inner edge, and said neck further being provided below the plane of said seat with inwardly 65 directed knobs or bosses extending inward beyond the said sharp edge of the rib or ledge.

In testimony whereof he affixes his signature.

ALBIN MILLER.
